UNITED STATES PATENT OFFICE.

JOHN A. WESER, OF NEW YORK, N. Y.

ADJUSTING DEVICE FOR PIANOS, PIANO-PLAYERS, &c.

1,159,630.

Specification of Letters Patent.

Patented Nov. 9, 1915.

Application filed March 22, 1913. Serial No. 756,101.

To all whom it may concern:

Be it known that I, JOHN A. WESER, a citizen of the United States, residing in the borough of Manhattan of the city of New York, in the State of New York, have invented certain new and useful Improvements in Adjusting Devices for Pianos, Piano-Players, &c., of which the following is a specification, reference being had 10 to the accompanying drawing, forming a part hereof.

In the actions of pianos and automatic piano-playing mechanisms, including not only the devices by which the hammers are actuated from the finger-keys of ordinary pianos, but also the devices by which the hammers are actuated from the player-pneumatics of automatic piano-playing mechanisms, considerable nicety of adjustment is 15 required, not only in the setting up of a new instrument, but from time to time as the instrument is used to compensate for changes due to wear and other causes. Such adjustments must usually be made by expert adjusters whose sense of touch has been trained by long experience, and the adjusting devices are usually not easily accessible.

The object of this invention is to provide an automatic adjusting device which requires 20 only to be freed by the adjuster so that the necessary adjustment or relative movement of parts to take up lost motion or looseness may be made automatically by the movement of the adjusting device itself and the parts then 25 re-secured in their adjusted positions.

The adjustment particularly referred to herein is that which must be made from time to time between a finger-key or a player-pneumatic and the corresponding abstract. 30 either directly or indirectly, but there are or may be other places or parts where or between which adjustment may be effected by a similar device. The adjustment, moreover, may be for the purpose of securing a 35 proper movement of one part with respect to another or of limiting the movement of one part.

The device comprises a contact piece movable by a spring to effect the desired movement of adjustment and means for securing such movable contact piece in position.

The invention will be more fully explained hereinafter with reference to the accompanying drawing in which several embodiments

of the invention are illustrated and in 55 which—

Figure 1 is a view in sectional elevation showing so much of an ordinary player-piano action as is necessary to enable the invention to be understood. Fig. 2 is a detail view on a larger scale illustrating more clearly the construction of the adjusting device. Fig. 3 is a detail view in elevation of a portion of the adjusting device. Figs. 4 and 5 are detail views illustrating still another embodiment of the invention.

The invention is illustrated in the drawing as applied to an upright player-piano of ordinary construction except so far as the present invention is concerned. A finger-key or key-lever *a* is shown as pivoted upon the key-base in the usual manner and adapted to engage in usual manner the usual abstract *b*. The latter is shown as connected at its upper end to a rocker *c* which carries 70 a jack *d* arranged to operate the hammer *e*, all as usual. Above the key-levers *a* are shown the ordinary player-pneumatics *g* which are connected with the wind ways and controlled from the tracker board as 80 usual.

In Fig. 1 of the drawing, each pneumatic is shown as having pivotally mounted thereon an adjusting finger or lever *h*, one end of which underlies and normally is in contact 85 with a corresponding cushioned block *b'* on the abstract, substantially as shown in Letters Patent of the United States No. 793,335, dated June 27, 1905. In that patent were shown means for adjusting the finger or 90 lever *h* with respect to the pneumatic, and although such means were readily accessible, nevertheless a nice adjustment of the free end of the finger with respect to the block on the abstract could be accomplished only 95 by the trained touch of an experienced adjuster. In the present case, however, the mere loosening of a single screw causes the finger to adjust itself automatically to take up lost motion between its free end and the 100 block on the abstract and the tightening of the screw secures the parts in adjusted position.

The adjusting device comprises a contact *i* which is shown in Figs. 1 and 2 as a 105 headed pin mounted in the end of the lever *h* nearest the adjuster and provided with a spring *k* to press the head of the pin toward

the pneumatic and consequently to press the corresponding end of the lever away from the pneumatic whenever the pin is free to move. The stem of the pin, in this construction, forms transversely through a block l which, as shown in Figs. 2 and 3, is seated in the end of the lever h and is provided with a binding screw m to secure the pin in its adjusted position. The spring k 10 is a light spring and serves only to move the free end of the lever h into contact with the block on the abstract without lifting the abstract, so that immediately upon loosening the screw m the necessary adjustment of the lever is effected automatically and such adjustment is retained by setting up the screw m .

To facilitate the phrasing of the claims so that the improved structure can be defined 20 succinctly and the invention distinguished from the prior art, it is well to give a definition of certain of the terms employed. Wherever it is stated that retaining means are employed for maintaining the spring under tension, it is meant that such means serve to make the spring entirely inactive so far as concerns any relative movement which it might tend to produce between the parts of the player action. Where it is stated 25 that the retaining means are operable to release the spring it is meant that after such manipulation the spring no longer exerts any pressure on the retaining devices but that it is exerted upon those parts of the 30 player action which it is desired to move a sufficient distance to take up the slack automatically. When the spring is thus released it acts to move the adjusting lever freely with respect to the movable member 35 of the pneumatic and without limitation of the movement of the adjusting lever by the retaining means.

In Fig. 1 of the drawing the lever h of the upper pneumatic is shown as in adjusted 40 position while the lever h of the lower pneumatic is shown as in a position which requires adjustment, there being lost motion between the free end of the finger and the block on the pneumatic.

In the construction shown in Figs. 4 and 50 5 the position of the pneumatic g^2 is reversed and the movable member of the pneumatic is shown as provided with a fixed finger h^2 which carries the gripping block l^2 provided with a binding screw m^2 . The 55 adjusting pin or rod i^2 passes through the block l^2 and is provided with a spring k^2 between the block l^2 and a collar k^2 . At its lower end the adjusting pin i^2 is operatively 60 connected with one end of a lever h^2 which is pivotally mounted and has its free end underlying a block on the abstract b , the ad-

justing device thus acting on a lever which is pivoted independently of the pneumatic instead of being on the pneumatic.

Various other embodiments of the invention will readily suggest themselves in view of the foregoing description and the invention, therefore, is not limited to the precise details of construction shown and described 65 70 herein.

I claim as my invention:

1. In a mechanism of the character described, the combination with the movable member of a player pneumatic, an abstract, 75 an adjusting lever pivoted on the movable member of the pneumatic and disposed operatively between said member and the abstract, a spring operatively interposed between the movable member and the lever, 80 means for maintaining the spring under tension, said means being operable to remove the pressure of the spring therefrom and to release the spring fully with respect to the lever whereby the spring acts on the lever 85 to move it freely with respect to said movable member of the pneumatic until the lever engages the abstract in normal operating position and thereby automatically takes up all looseness between the pneumatic and 90 the abstract.

2. In a mechanism of the character described, the combination with the movable member of a player pneumatic, an abstract, 95 an adjusting lever pivoted on the movable member of the pneumatic and disposed operatively between said member and the abstract, a freely movable contact piece interposed between the lever and the movable member of the pneumatic and carried by 100 either the lever or said movable member, a spring abutting against either the lever or the movable member and acting upon the contact piece to produce movement of the lever, and means for securing the contact 105 piece in adjusted position.

3. In a mechanism of the character described, the combination with the movable member of a player pneumatic, an abstract, 110 an adjusting lever pivoted on the movable member and extended beyond the member to engage the abstract, a pin carried on the opposite end of the lever and engaging the movable member, a spring acting on the pin to cause movement of the lever, and a screw 115 to secure the pin releasably in adjusted position.

This specification signed and witnessed this 21st day of March A. D., 1913.

JOHN A. WESER.
